UNITED STATES PATENT OFFICE.

ROBERT HARRIS, OF LONDON, ENGLAND, ASSIGNOR OF ONE-HALF TO PICTORIAL MACHINERY LIMITED, OF LONDON, ENGLAND, A BRITISH COMPANY.

DUPLICATING OR PRINTING APPARATUS AND PARTICULARLY PHOTOGRAPHIC STEP-AND-REPEAT CONTACT-PRINTING APPARATUS.

Application filed June 10, 1927, Serial No. 197,790, and in Great Britain August 11, 1926.

This invention relates to duplicating or printing apparatus, and particularly photographic step-and-repeat contact-printing machines. In such machines a unit-holder carrying a unit, such as a photographic negative or positive, and a support constituting a bed for a sensitive surface, such as a plate of sensitized metal, e. g. zinc or aluminium, have been arranged one fixed against movement in its own plane and the other movable in relation thereto to permit the unit to be brought into intimate contact with various parts of the metal plate in succession. When the bed is stationary and of large dimensions the unit-holder has to have a large range of motion in at least two directions. In one such machine proposed heretofore a stationary main frame for the bed was provided with a longitudinal track extending in the direction of length of the bed, on which track ran a carriage having a transverse track extending across the bed, along which transverse track the light box having the unit-holder was movable. Such an arrangement has the drawback that any defect such as lack of alignment in the longitudinal track, due e. g. to wear and tear, affects also the transverse track with the result that the directions of the relative movements of the bed and light box will vary so much from a right angle as to destroy all possibility of exact register of the various prints produced on the machine. Also in the machine referred to the track of the carriage carrying the light box extended along two opposite longitudinal edges of the bed and constituted an obstacle to an operator who desired to work along both gripper edges. Further, if the unit-holder is fixed the large bed is heavy and cumbrous to move into the required positions.

This invention has for its main object to obviate these defects even when beds of large size, say $3\frac{1}{2}$ feet by $4\frac{1}{2}$ feet, are used; other objects are to facilitate the unit-holder and bed being correctly positioned in relation one to the other after each movement, and to enable such changes of position to be made in rapid succession.

According to an important feature of the invention, there is provided duplicating or printing apparatus, for example photo-

graphic step-and-repeat contact-printing apparatus, wherein a supporting device (e. g. a table) for a printing member (e. g. a plate), and a unit-holding device for carrying a unit (e. g. a carriage for a photographic negative) are so arranged on a framework that the unit can be brought into contact with different parts of the printing member in succession, characterized in that two independent tracks are provided on the said framework lying transversely one of the other (e. g. at right-angles to one another), on one of which tracks the said supporting device is mounted to reciprocate, and on the other of which tracks the said unit-holding device is mounted to reciprocate, and two driving mechanisms are mounted independently one of the other on said framework and associated each with one of said tracks for driving the device thereon. Owing to this arrangement any defect in one track is not communicated to the device carried by the other track, and the machine lends itself to more exact register of one print with another than has been obtained heretofore even when a certain amount of wear in one or both tracks occurs.

According to another feature of the invention, either of the tracks aforesaid and the device, namely the supporting device or the unit-holding device thereon, is combined with a fine-adjustment stop that is adjustable in the direction of length of one of said tracks and is arranged to coact with and arrest the said device (e. g. the supporting device or the unit-holding device) thereon, resilient driving mechanism for driving said device up to and holding it resiliently against said fine-adjustment stop, and locking means for locking said device temporarily in its position of adjustment against said fine-adjustment stop, for the purpose of ensuring that the device that is being set shall be held home against the fine-adjustment stop whilst the device is being locked in the position in which it is thereby set.

According to yet another feature of the invention, each driving mechanism extends from end to end of its associated track and has operating means (e. g. toothed wheel gearing) at each end thereof, which operating means are each so arranged that it can

actuate the driving mechanism in both directions, and two arresting means (e. g., pawl-and-ratchet mechanisms) associated each with one of said operating means normally prevent the operating means from operating the driving mechanism in either direction. This arrangement enables the device on a track to be controlled from either end of the latter, and an operator at one end of the track can prevent the device thereon from being driven by an unauthorized person at the other end of the track.

According to a further feature of the invention, the driving mechanism comprises an endless member (e. g. an endless chain) arranged alongside the track, a spring (e. g. a coil spring surrounding a part of the endless member) constitutes a driving connection between said device (e. g. the supporting device) and the endless member, and arresting means (e. g. pawl-and-ratchet mechanism) is arranged to hold the endless member against the action of said spring.

It is a further feature of the invention to provide in combination with the parts set forth above, a coarse-adjustment stop movable into the path of a said device (e. g. the supporting device) and arranged to arrest the latter approximately at an initial position on the track, and means (e. g. a rack-and-pinion mechanism) for removing said coarse-adjustment stop into an inoperative position.

Conveniently, one end of the track of said supporting device extends through an aperture in a wall of a photographic dark room, and a light-tight casing fitting said aperture encloses the remainder of said track and the said supporting device movable thereon.

The invention also provides a method of positioning on a track a device such as a unit-holding device, or a bed for a press plate, in duplicating or printing apparatus, for example photographic step-by-step contact-printing apparatus, which consists in setting a fine-adjustment stop in a predetermined position in the path of movement of the device, driving the device (e. g. by resilient driving means) up to and holding it, preferably resiliently, against said stop by said driving means, clamping the device against movement in the adjusted position against said stop, setting the said stop in a fresh predetermined position in the path of movement of the device on the track, unclamping the device and repeating the cycle of operations.

According to another feature of the invention, the method set forth in the preceding paragraph comprises the steps of arresting the device approximately in its initial position by a coarse-adjustment stop, and rendering the latter inoperative after the fine adjustment stop has become operative.

The invention will now be described with

reference to the accompanying drawings which diagrammatically illustrate by way of example one form of photographic step-and-repeat contact-printing machine constructed according to the invention. In said drawings:

Figure 1 is a perspective view of the machine as seen from one side at the front end thereof, and

Figure 2 is a like view of the machine as seen from the other side at the rear end thereof;

Figure 3 is a diagrammatic side elevation of a track aforesaid with the supporting device thereon and the setting mechanism associated therewith.

Figure 4 is a plan view, and

Figure 5 an end elevation of the parts shown in Figure 3.

Like reference numerals designate like parts throughout the several views.

Referring to the drawing, a photographic step-and-repeat contact-printing machine comprises a framework 10 having two tracks 11, 12, a lower one 11 extending in the direction of length of the machine, and an upper shorter one 12 lying at right angles thereto. One end of the lower track 11, hereinafter referred to as the front end, extends through an aperture 13 in a wall 14 which forms part of a light-tight casing 15 that encloses the remainder of the lower track for the purpose described hereinafter. When the machine is in use this wall constitutes part of the wall of a photographic dark room.

A table 20 having a bed 21 for supporting a sensitized metal plate 22, for example of zinc or aluminum, is arranged to run on wheels 23 or rollers on the lower track 11 and can be loaded in the dark room when on the front end thereof. A carriage 30 that carries a press frame for a negative and a light box 31 with a lamp for illuminating the negative is arranged to run on the upper track. By traversing the bed 21 and carriage 30 each along its track the negative can be brought step by step into various positions in succession above the sensitized plate 22 from which light other than that from the lamp is excluded.

In order that the printing of the plate may be effected with exact repetition and register in whatever positions may be required, that is according to the various sizes of plate and negative, and in order that the setting operation may be partly performed during the printing operation, setting means operable independently of the table 20 and carriage 30 are associated with each track. These setting means are of similar construction for each track and will now be described with reference to the lower track 11 and its table 20.

As diagrammatically shown in Figures 3

to 5, an endless chain 40 is carried on sprocket wheels 41, 42, one at each end of the track, and has a resilient driving connection with the table near the rear end of the latter. As illustrated, the bottom of the table carries a hollow cylindrical guide 43 having in the middle of its length a partition 44 through which a rod 45 constituting a link of the chain extends. Two coil springs 46, 47 surround the rod 45 and abut at one end against said partition 44 and at their other ends each against one of two collars 48 fast on the ends of the rod. A coarse-adjustment stop 50 in the form of a vertical latch having its lower end formed as a toothed rack can be brought into and out of its operative position on the track by a pinion 51 that engages the rack and can be rotated by hand by a spindle 52 that extends out of the casing at one side of the machine and carries a handle 53. When this latch 50 is in its operative position the front end of the table 20 coming from the dark room can ride over and fall behind it and be temporarily held in an initial position indicated in Figure 3. When so positioned an abutment 54 in the form of a tapered plug held in the bottom of the table is located against a fine-adjustment stop 55 which is carried by a nut 56 movable on a screw spindle 57 that carries an index movable by a handle 58 over a graduated dial 59 at the rear end of the track, so that the fine-adjustment stop 55 can be accurately adjusted in any desired position along the length of the spindle independently of the movement of the table. Owing to the stop 55 being adjustable independently of the traveling table it can be adjusted to a new position whilst the table is locked in its adjusted position and is being used for printing purposes. This ensures a saving of time as compared with an arrangement wherein the travelling table or light box itself has to be set by means of index mechanism.

Pawl-and-ratchet mechanism 60, 61 is provided at each end of the track for driving the endless chain. At the front end, namely in the dark room this mechanism 60 comprises two spur gears 62, 63, substantially equal in diameter, whereof one, 62, is co-axial with the adjacent sprocket wheel 41 and the other, 63, is co-axial with a ratchet wheel 65 controlled by a spring-pressed pawl 66 so as to be rotatable only clockwise, when the pawl is operative, and drive the table backwards, namely towards or into the dark room. In order to rotate the ratchet wheel counter-clockwise to drive the table forwards the operator has to pull the pawl 66 back against its spring, in which retracted position it can be held against a stop by giving it a half turn. The pawl-and-ratchet mechanism 61 at the rear end of the track is constructed similarly (similar parts

being indicated by like reference numerals), except that it constitutes speed-reduction gear, and when the pawl 66 is operative can drive the table towards the rear, a counter-shaft 67 carrying two gear wheels 68, 69 of different diameter being provided between the said spur gear 62, 63. This arrangement enables the traversing movement of the table 20 to be effected from either end of the framework 10, but enables an operator at either end to prevent such movement in both directions by locking the pawl-and-ratchet mechanism against rotation.

The locking device aforesaid may be in the form of a friction clutch comprising two clutch plates or discs 70, 71 one at each side of a web 72 on the bottom of the table extending along the middle or one side thereof. A rod 73 carrying the plate 70 at one side of the web is slidable endwise in a tube 74 carrying the other plate 71, which tube is fixed against endwise movement in a sleeve 75 secured on the side of the track 11. The rod and tube are rotatably coupled together at their outer ends by a handle 76 having a pin that engages radially in a cam slot 77 in the adjacent end of the sleeve, so that by turning the handle the clutch is caused to grip the web on the table. Alternatively, the rod may be screw-threaded in the tube, and the tube may be threaded in the opposite sense in the sleeve, a single handle being arranged to rotate both rod and tube simultaneously.

As indicated above, similar driving and adjusting mechanism is associated with the other track 12 for driving the light-box carriage and for setting the negative holder in various positions in relation to the table.

When the bed 21 on the table 20 is being loaded in the dark room, the coarse-adjustment stop 50 will be in its operative position in relation to the track 11. When the plate 22 has been clipped on the bed 21 the operator in the dark room will release the pawl 66 of the ratchet mechanism 60 at the front end of the track 11 and drive the endless chain 40 so as to drive the table out of the dark room through the aperture 13 in said wall 14 to near the centre of the track 11 under the carriage 30 until the one end of the table rides over the coarse-adjustment stop 50, which will be felt by the operator. The fine-adjustment stop 55 will have been previously set for the initial position of the table and owing to the resilient drive by the chain the abutment 54 on the table will be held resiliently against the fine-adjustment stop, whereby the table will be accurately positioned in its initial position. The chain 40 cannot move in the reverse direction owing to its being held against such movement by the pawl-and-ratchet mechanism 61 at the rear end of the track 11. The table will now be locked in its initial position by

the clutch 70, 71. When so locked the coarse-adjustment stop 50 can be removed into an inoperative position, and the fine-adjustment stop 55 can be reset for a second position by the index mechanism 58, 59 at the rear end of the track. When so set the clutch 70, 71 will be released and the table will be moved up to the fine-adjustment stop 55 in its new position by operating the pawl-and-ratchet mechanism 61 at the rear end of the track, when the table will be again locked in its second position. This operation can be repeated as many times as is necessary, and when the table has arrived into its rear end position and printing has been effected the table can be returned rapidly into the dark room by turning the handle 80 of the pawl-and-ratchet mechanism 60 or more slowly by turning the handle 81 of the pawl-and-ratchet mechanism 61.

The carriage 30 can be traversed on its track in a like manner. The handles 80, 81, 76, 53 for operating the ratchet mechanism, the locking device and the coarse-adjustment stop associated with the track 11 are arranged at the same side thereof so as to facilitate the operation of the machine; the corresponding handles 180, 181, 176 and 153, associated with the upper track 12 are shown in Figure 1, and also index mechanism 158, 159 corresponding to the index mechanism 58, 59. A fine-adjustment stop 155, nut 156 and spindle 157 associated with the carriage 30 and corresponding to the parts 55, 56 and 57 are shown in Figure 2 situated along one side of the track 12. Owing to the described light-tight enclosure the sensitized plate 22 is protected from exposure to daylight in all its positions on the track.

An important advantage of the invention is that whilst contact printing of the plate is being effected with the table and light-box in one position the various manipulations requisite for setting the table and carriage in a second position can be performed whilst such printing is taking place, when it is only necessary to move the table and carriage up to the newly adjusted stops, whereby a considerable saving in time is effected. Further, owing to the resilient drive described above all backlash and lack of proper contact between the stops and the parts co-operating therewith are effectively prevented, whereby correct positioning of the table and carriage is ensured.

Various modifications in the details of construction described above may be made without departing from the scope of the invention as defined in the claims.

I claim:

1. In apparatus of the character described, the combination of a framework having two independent tracks lying transversely one of the other, a supporting device

for a printing member mounted to reciprocate on one of said tracks, a unit-holding device for carrying a unit mounted to reciprocate on the other of said tracks, a fine-adjustment stop adjustable in the direction of length of one of said tracks, resilient driving mechanism arranged to drive the device on the latter track up to and hold it resiliently against said stop, locking means for locking the latter device temporarily in its position of adjustment against said stop, and a second driving mechanism distinct from said resilient driving mechanism and mounted independently thereof in association with the other track and arranged to drive the device on the latter.

2. In apparatus of the character described, the combination of a framework having two independent tracks lying transversely one of the other, a supporting device for printing member mounted to reciprocate on one of said tracks, a unit-holding device for carrying a unit mounted to reciprocate on the other of said tracks, and two distinct driving mechanisms mounted independently one of the other on said framework and associated each with one of said tracks and arranged to drive the device thereon, each of which driving mechanisms extend from end to end of its associated track and comprises two operating means, one near each end of the track, arranged to actuate its associated driving mechanism in both directions, and two arresting means associated each with one of the operating means normally preventing the latter from operating the associated driving mechanism in either direction.

3. In an apparatus of the character described, the combination of a framework having two independent tracks lying transversely one of the other; a supporting device for a printing member mounted to reciprocate on one of said tracks, a unit-holding device for carrying a unit mounted to reciprocate on the other of said tracks, a fine-adjustment stop adjustable in the direction of length of one of said tracks, resilient driving mechanism arranged to drive the device on the latter track up to and hold it resiliently against said stop, locking means for locking the latter device temporarily in its position of adjustment against said stop, which driving mechanism comprises two operating means in the form of toothed wheel gearing, one near each end of the said track, and two arresting means associated each with one of said operating means and normally preventing the driving mechanism from moving in either direction, and a second driving mechanism distinct from said

resilient driving mechanism and mounted independently thereof in association with the other track and arranged to drive the device on the latter.

4. In apparatus of the character described,

- the combination of a framework having two independent tracks lying transversely one of the other, a supporting device for a printing member mounted to reciprocate on one of said tracks, a unit-holding device for carrying a unit mounted to reciprocate on the other of said tracks, a fine-adjustment stop adjustable in the direction of length of one of said tracks, resilient driving mechanism arranged to drive the device on the latter track up to and hold it resiliently against said fine-adjustment stop, locking means for locking the latter device temporarily in its position of adjustment against said fine-adjustment stop, which driving mechanism comprises an endless member arranged alongside said track, a spring constituting a driving connection between said endless member and the device on said track, and arresting means for holding said endless member against the action of said spring, and a second driving mechanism distinct from said resilient driving mechanism and mounted independently thereof in association with the other track and arranged to drive the device on the latter.
5. In apparatus of the character described, the combination of a framework having two independent tracks lying transversely one of the other, a supporting device for a printing member mounted to reciprocate on one of said tracks, a unit-holding device for carrying a unit mounted to reciprocate on the other of said tracks, a fine-adjustment stop adjustable in the direction of length of one of said tracks, resilient driving mechanism arranged to drive the device on the latter track up to and hold it resiliently against said stop, locking means for holding the latter device temporarily in its position of adjustment against said stop, and a second driving mechanism distinct from but substantially a duplicate of said resilient driving mechanism and mounted independently thereof in association with the other track and arranged to drive the device on the latter.
6. In apparatus of the character described, the combination of a framework having two independent tracks lying transversely one of the other, a supporting device for a printing member mounted to reciprocate on one of said tracks, a unit-holding device for carrying a unit mounted to reciprocate on the other of said tracks, a coarse-adjustment stop movable into the path of the device on one of said tracks and arranged to arrest the device approximately at an initial position on said track, means for removing said coarse-adjustment stop into an inoperative position, a fine-adjustment stop adjustable in the direction of length of said track, resilient driving mechanism arranged to drive the device on the latter track up to and hold it resiliently against said fine-adjustment stop, locking means for locking the latter device temporarily in its position of adjustment against said fine-adjustment stop, and a second driving mechanism distinct from said resilient driving mechanism and mounted independently thereof in association with the other track and arranged to drive the device on the latter.
7. In apparatus of the character described, the combination of a framework having two independent tracks lying transversely one of the other, a supporting device for a printing member mounted to reciprocate on one of said tracks, a unit-holding device for carrying a unit mounted to reciprocate on the other of said tracks, a fine-adjustment stop adjustable in the direction of length of one of said tracks, resilient driving mechanism arranged to drive the device on the latter track up to and hold it resiliently against said stop, which latter device has a web extending in the direction of movement thereof, locking means in the form of a clutch that is carried by said framework and is arranged to engage said web for locking the said device temporarily in its position of adjustment against said stop, and a second driving mechanism distinct from said resilient driving mechanism and mounted independently thereof in association with the other track and arranged to drive the device on the latter.
8. In apparatus of the character described, the combination of a framework having two independent tracks lying transversely one of the other, a supporting device for a printing member mounted to reciprocate on one of said tracks, a unit holding device for carrying a unit mounted to reciprocate on the other of said tracks, and two distinct driving mechanisms mounted independently one of the other on said framework and associated each with one of said tracks and arranged to drive the device thereon, a wall of a photographic dark room having an aperture through which extends one end of the track of said supporting device, and a light-tight casing that fits said aperture and encloses the remainder of the latter track and the said supporting device movable thereon.

In testimony whereof I affix my signature.

ROBERT HARRIS.
